No. 37,197.

Patented October 25, 1904.

UNITED STATES PATENT OFFICE.

GIBBS MASON, OF NEW YORK, N. Y., ASSIGNOR TO KEYSTONE TYPE FOUNDRY, OF PHILADELPHIA, PENNSYLVANIA, A COPARTNERSHIP.

DESIGN FOR A FONT OF PRINTING-TYPE.

SPECIFICATION forming part of Design No. 37,197, dated October 25, 1904.

Application filed September 13, 1904. Serial No. 224,341. Term of patent 7 years.

To all whom it may concern:

Be it known that I, GIBBS MASON, a citizen of the United States, and a resident of New York, in the county of New York and State of New York, have invented a new, original, and ornamental Design for a Font of Printing-Type, as shown in the accompanying drawing, representing a typographical impression of said type.

I claim—

The ornamental design for a font of printing-type, as herein shown.

GIBBS MASON.
